ADJUSTABLE PISTON EXPANDER

Fred E. Milner, Ossian, Ind.

Application January 29, 1938, Serial No. 187,777

9 Claims. (Cl. 309—12)

This invention relates to piston expanders used for expanding the skirt of a longitudinally split piston and particularly to an adjustable resilient expander.

5 Pistons have split skirts for the purpose of taking care of expansion. After a motor has been in use for a time, the piston becomes worn and distorted and "slap" develops. Loss of compression results and oil consumption is increased.

10 Various devices have been devised for the purpose of expanding the skirt of the piston under these circumstances, but it is a requirement of a piston expander that it shall be adjustable for every piston inasmuch as no two pistons have 15 exactly the same characteristics of expansion and contraction nor will two pistons wear to exactly the same extent.

The general object of the present invention is to provide a piston expander that can be readily 20 installed and have means of adjustment to take care of all the differences of expansion and contraction in individual pistons.

A further object is to provide a piston expander 25 which will engage the piston skirt on each side of the slot at two points so that the skirt may be expanded either adjacent the head or adjacent the end of the piston skirt or both.

A still further object is to provide means for 30 adjusting this skirt either adjacent the head or adjacent the end of the skirt and either uniformly or differentially.

Still another object is to provide a device of 35 this character which is adaptable to many different sizes and types of pistons and to differences 5 to wear.

Other objects will appear in the course of the following description.

My invention is illustrated in the accompanying drawing wherein:—

40 Fig. 1 is a longitudinal sectional view through a piston and illustrating my expander applied to the skirt of the piston, portions of the expander being in section.

45 Fig. 2 is a section on the line 2—2 of Fig. 1.

Fig. 3 is a fragmentary longitudinal section through one wall of the skirt showing an expander rod in elevation and illustrating the means whereby it is connected to the piston and skirt.

50 Fig. 4 is a section on the line 4—4 of Fig. 1.

Fig. 5 is a face view of the expander with the wedges disposed equi-distantly.

55 Fig. 6 is a fragmentary sectional view through the collar showing the standing bars in elevation and illustrating notches on the bars for holding

the collars and bars in adjusted position relative to each other.

Referring to this drawing, A designates a piston head having a skirt B which is longitudinally slotted at C. I do not wish, of course, to limit 5 myself to the particular type of piston disclosed as the expander which I am about to describe is adaptable to many different types of pistons having a split skirt.

My expander comprises two expanding bars 10 10 and 11 of steel wire. These bars are bowed towards each other and each bar at its upper end is formed with a coil 12, the extremity of the coil terminating in an outwardly extending portion 13 which is inserted into a drilled opening 15 in the skirt of the piston, as shown in Fig. 3. After the extremity 13 has been inserted in this drilled opening, the outer end of this portion 13 is worked down by filing or otherwise so that it does not project, of course, in any way beyond the 20 outer surface of the piston. The opposite ends of each of the expansion bars 10 is formed with an S-shaped coil to provide an eye 14 adapted to embrace a rivet 15. The head of this rivet is set in a small countersink 16 formed in the skirt 25 so that the head of the rivet will not project outward beyond the outer surface of the skirt. As before remarked, the expanding bars 10 are inwardly bowed towards each other and intermediate the ends of the expanding bars they are 30 connected by means of a sliding ferrule or collar designated 17. Disposed above and below the ferrule or collar 17, that is, on each side of the ferrule or collar are the wedges 20 and 21. These wedges are both alike. The wedge 21 is formed 35 with a longitudinally extending passage 22 which is unscrew-threaded. The wedge 20, however, is formed with a longitudinally extending passage 23 which is interiorly screw-threaded. Each of these wedges upon its outer face is formed with 40 a groove 24. Extending loosely through the passage 22 is an adjusting screw 25 having a head 26 at one end and having its outer port remote from the head screw-threaded at 27. These threads 27 engage with the threads on the interior of the bore 23 but the screw passes loosely through the passage 22 and loosely through the passage defined by the collar 17. The head 26 bears against the adjacent end of the wedge 21 as illustrated in Fig. 1. 50

With this construction it is possible to dispose the wedges 20 and 21 each at the same distance from the ferrule or collar 17 and dispose the ferrule or collar at the middles of the two expansion bars 10 and then by turning the screw 27 to force 55

both of the wedges uniformly towards each other, thus causing an expansion of the outer ends of the expansion bars and the consequent uniform widening of the slot C in the piston skirt. On 5 the other hand, it is possible, with this construction, to shift the screw through the collar or ferrule 17, leaving this ferrule still at the middle of the expansion bars, thus causing the wedge 20 to engage the expansion bars nearer to the collar 10 or ferrule 17 than the wedge 21, then by rotating the screw the wedges are moved inward, but a greater expansion will be given to the ends of the expansion bars adjacent the head of the piston than to the ends of the expansion bars adjacent 10 the end of the skirt. Vice versa, it is possible, of course, to adjust the screw 27 nearer to the head of the piston and thus cause the wedge 20 to be disposed at a greater distance from the collar or ferrule 17 than the wedge 21, thus causing a 15 greater expansion of the outer ends of the expansion bars than of the inner ends. It is also possible to shift the collar or ferrule 17 along the expansion bars and then adjust the screw 25 and the wedges to any desired predetermined position 20 so as to secure a proper adjustment of the expansion bars to in turn secure a differential adjustment of the slot C adjacent its opposite ends. 25

It will be understood, of course, that the expansion bars tend to contract the piston skirt 30 by reason of their resilience or, in other words, if the wedges 20 and 21 were omitted or were disposed as far as possible apart, the bars 10 and 11 would tend to contract the piston skirt. The action of the wedges is to force these 35 expansion bars 10 and 11 apart either uniformly or differentially and thus increase to any desired extent the width of the slot C. The grooves 24 in the wedges act to hold the expansion bars firmly in place and move the expansion bars accurately when the wedges are adjusted. The head 26 of the screw is nicked or otherwise formed for the application of a screw driver or other turning implement and is apertured at 28 for keying. The outwardly extending extremities 13 at the upper ends of the expansion bars 10 and 11 and the rivets 15 at the lower ends hold the expansion bars firmly in place and makes it impossible for them to come loose or get out of place. 45

This device can be installed very quickly and by its means either a uniform or non-uniform expansion or adjustment of the piston skirt may be readily made. This secures long life for the piston and a perfect fit. Furthermore, it will 50 be seen that my expander does not merely engage at two points on opposite sides of the slot C but engages at four points, two points adjacent the head of the piston and two points adjacent the opposite end of the skirt so that uniform expansion or contraction can be secured, if desired. With my construction after my adjustable piston expander has been put in place, it can be adjusted without removing the expander from the piston because of the fact that 55 the collar or ferrule 17 is adjustable along the expansion bars and that the wedges are adjustable. Thus either the wedges or the wedges and the collar 17 may be adjusted longitudinally on the expansion bars so as to secure expansion exactly where it is needed. All expanders known to me only expand where they are attached to the piston, thus if they are attached adjacent the free end of the piston skirt, it will be this free end which will be expanded the most. 60 If they are attached adjacent the head of the 75

piston, it will be the head of the piston where the force is applied and if the slot is expanded at this point, the slot in the end of the piston skirt will be expanded to a greater degree than is necessary. Inasmuch as the middle portion 5 of my expanding bars cannot expand because of the collar, it follows that there may be differential adjustment both inward of this collar and outward of this collar at two separated points on the piston skirt. 10

Preferably, and in order to secure a positive interlock between the collar or ferrule 17 and the expander bars 10 and 11, the ferrule is formed as shown in Fig. 6, with opposed inwardly projecting teeth 29, and the bars 10 and 11 are formed with a plurality of notches 30, these notches being shown as five in number, thus providing a middle notch and several notches on each side of the middle. These notches are preferably about $\frac{1}{8}$ " apart, but may be spaced at a less distance if desired. This provides a positive means for locking the bars 10 and 11 and the collar in relatively adjusted positions. 15

It will be noted that the upper ends of the 25 bars 10 and 11 are coiled and then have the outwardly extending portions 13 engaging the wall of the piston whereas the lower ends of the expanding bars are formed with an S-shaped bend defining eyes by which the expanding bars are 30 riveted to the wall of the piston. The reason for this difference is that it would be impossible to rivet the upper ends of these bars quickly to the piston skirt and it would not do to hook both the upper and lower ends to the piston 35 skirt because of the danger of twisting up and coming unhooked. The coils 12 help to brace the hook ends and cause the terminal ends 13 to stay in place. This spiral coil also gives flexibility and resilience. The S-shaped coils or 40 bends at the lower ends of the bars 10 and 11 give the necessary flexibility at these points and secures more flexibility at the lower ends of the bars than at the upper. This is for the reason that a split piston requires more flexibility at 45 the lower end of an expander than at the upper end thereof. By riveting the lower ends of the bars 10 and 11 to the piston wall, it is assured that these ends will not come off as so often happens with other piston expanders now in 50 use that only hook on the wall of the piston. By riveting these ends 14 to the piston, it will be impossible for the expander to twist and thus hold the portions 13 at the upper ends of the 55 bars firmly in place within the wall of the piston.

What is claimed is:—

1. The combination with a piston having a longitudinally slotted skirt, of an expander comprising two longitudinally extending elements 60 bowed inward towards each other, each element being connected to the skirt of the piston at both ends, the elements being disposed one on each side of the slot in the skirt, means connecting the elements intermediate their ends, wedges disposed between the elements and bearing against the same and located on each side of the connecting means, and means for simultaneously adjusting the said wedges toward or from said connecting means. 65

2. The combination with a piston having a longitudinally slotted skirt, of an expander comprising two longitudinally extending resilient elements bowed inward towards each other, each element being connected to the skirt of the piston 70 75

at both ends, the elements being disposed on each side of the slot, the resilience of the elements tending to contract the skirt of the piston, and means whereby the elements may be forced apart at their opposite ends.

5 3. The combination with a piston having a longitudinally slotted skirt, of an expander comprising two longitudinally extending resilient elements bowed inward towards each other, each 10 element being connected to the skirt of the piston at both ends, the elements being disposed on each side of the slot, the resilience of the elements tending to contract the skirt of the piston, a collar connecting the elements intermediate their 15 ends, wedges disposed between the elements and located on opposite sides of the collar, the wedges bearing against the elements, and a screw whereby said wedges may be drawn towards or forced away from each other.

20 4. The combination with a piston having a longitudinally slotted skirt, of an expander comprising two longitudinally extending resilient elements bowed inward towards each other, each element being connected to the skirt of the piston 25 at both ends, the elements being disposed on each side of the slot, the resilience of the elements tending to contract the skirt of the piston, a collar connecting the elements intermediate their ends, wedges disposed between the elements and 30 located on opposite sides of the collar, the collar having a passage through which the elements loosely pass, and a screw engaging the wedges and passing loosely through said collar.

35 5. The combination with a piston having a longitudinally slotted skirt, of an expander comprising two longitudinally extending resilient elements bowed inward towards each other, each element being connected to the skirt of the piston at both ends, the elements being disposed on 40 each side of the slot, the resilience of the elements tending to contract the skirt of the piston, a collar connecting the elements intermediate their ends, wedges disposed between the elements and located on opposite sides of the collar, the 45 collar having a passage through which the elements loosely pass, and a screw passing loosely through the collar having threads at one end engaging the innermost wedge and passing loosely through the outermost wedge but provided with a head engaging against the outermost wedge.

50 6. The combination with a piston having a longitudinally slotted skirt, of an expander comprising two longitudinally extending resilient in-

wardly bowed elements, each of said elements at its end adjacent the head being formed with a coil and being engaged with the wall of the skirt, each of said elements at its outer end being coiled and rigidly engaged with the wall of the skirt, 5 a collar having a passage through which said elements pass, wedges disposed on each side of the collar and engaging said elements, and a screw engaging said wedges and passing loosely through the collar.

10 7. A piston expander comprising two inwardly bowed resilient bars, each bar having means at its opposite ends whereby it may be rigidly connected to a piston skirt with the bars disposed on opposite sides of the slot of the skirt, a collar connecting said bars intermediate their ends, a screw passing loosely through the collar and wedges disposed one on each side of the collar and engaging between the inwardly bowed portions of the bars with which the screw engages.

15 8. A piston expander comprising two inwardly bowed resilient bars, each bar having means at its opposite ends whereby it may be rigidly connected to a piston skirt with the bars disposed on opposite sides of the slot of the skirt, a collar 20 connecting said bars intermediate their ends, a screw passing loosely through the collar, and wedges disposed one on each side of the collar and engaging between the inwardly bowed portions of the bars with which the screw engages, 25 the screw passing loosely through the outermost wedge but having screw-threaded engagement with the inner wedge.

30 9. A piston expander, including two inwardly bowed resilient bars adapted to be disposed one on each side of the slot of a piston skirt, each of said bars at its inner end being coiled and then extended outward to pass through a bore in the piston skirt, the opposite end of each bar being formed with an S-shaped coil constituting an eye 35 40 adapted to be riveted to the piston skirt and a collar, the bars passing loosely through the collar, wedges disposed on each side of the collar and grooved on their edges to receive the bars, a screw passing loosely through the collar and having a head at one end and a screw-threaded portion at the opposite end, the screw having threaded engagement with the inner wedge but passing loosely through the outer wedge, the head of the screw bearing against said outer wedge, and 45 means whereby said screw may be rotated and 50 keyed.
